M. CAGGIANO,
SAFETY DEPOSITORY FOR MILK BOTTLES,
APPLICATION FILED FEB. 28, 1917.

1,240,308.

Patented Sept. 18, 1917.

Inventor

Michael Caggiano
By his Attorney

Francis X. Manuse

UNITED STATES PATENT OFFICE.

MICHAEL CAGGIANO, OF NEW YORK, N. Y.

SAFETY-DEPOSITORY FOR MILK-BOTTLES.

1,240,308.

Specification of Letters Patent. Patented Sept. 18, 1917.

Application filed February 28, 1917. Serial No. 151,401.

To all whom it may concern:

Be it known that I, MICHAEL CAGGIANO, a citizen of the Kingdom of Italy, and a resident of New York, county of New York, 5 and State of New York, have invented certain new and useful Improvements in Safety-Depositories for Milk-Bottles, of which the following is a specification.

This invention has reference to improvements in safety depositaries for milk bottles which are adapted to hold the same safely after having been deposited therein by the distributing milk man.

The purpose of the present invention is to 15 prevent the loss of milk by theft. For this purpose the novel safety depository is so constructed as to be applied to or hung on the top rail or the top of the lock stile of the door frame. If the door is closed the 20 depository can not be removed nor a milk bottle therein because the depository is held tight between the top of the door and the adjoining wood-work or part of the wall, and the cover of the device can not be lifted 25 until the door is opened and the device removed. Means are provided in the bottom portion of the depository allowing a milk bottle to pass when shifted in and supporting it until removed from the top. Another 30 feature of the invention is that one milk bottle may be deposited within the device and one safely suspended in the means for holding it just mentioned. The depository being hung on the door renders it unnecessary to cut, drill or otherwise injure and disfigure the door for the purpose of applying thereto a milk depository. These and other 35 features will be fully described hereinafter with reference to the accompanying drawing in which:

Figure 1 represents in central longitudinal section a safety depository as applied to a door with one milk bottle therein and a second one held and suspended thereby. 45 Fig. 2 is a detail view in central section of the top portion of the depository with the cover or lid partly opened.

Fig. 3 is a cross section on line 3—3 of Fig. 1 without any bottle in the depository. 50 Similar characters of reference denote like parts in all the figures.

In the drawing, *a* represents a tubular receptacle of such diameter as to conveniently hold a full sized milk bottle. In the 55 bottom portion of the tube *a* there is permanently secured a circular strip of metal *b*

preferably by small rivets *c*. As shown in Figs. 1 and 3 this circular strip of metal is located on the inside of the bottom portion of the tube *a* and has formed thereon a 60 plurality of leaf springs *d* integral therewith and curved upwardly and inwardly as shown in Fig. 1. This system of leaf springs thus is radially arranged with the narrowest portion near the center where it leaves an 65 opening *e*, as best shown in Fig. 3.

The top of the tube *a* is provided with a cover or lid *f* secured thereto by a hinge *g*, as shown in Figs. 1 and 2, one hinge leaf being secured to the inner top surface of 70 the tube *a* and the other to the bottom surface of the cover *f*. At either side of the hinge and secured to the bottom surface of the cover there are two metal strips of which one *h* is shown in the drawing. These metal 75 strips rise upwardly beyond the tube near the hinge *g* where the tube is somewhat cut to allow of the passage of the metal strips *h* and of the convenient location of the hinge. The upwardly rising portion *h*¹ of the metal 80 strip *h* is again bent at a right angle and forms a horizontal portion *h*². Each portion *h*² again is bent at a right angle downwardly forming a curved section *h*³, as indicated at *h*⁴. The described device forms a 85 combined hinged cover and hook to suspend it on the top rail or lock stile of the door frame *i*. As shown in Fig. 1 it is impossible to remove the safety depository when 90 the door is closed as during the night.

When the milk man comes in the morning he pushes one bottle of milk *j* from below through the leaf spring device into the tubular receptacle *a* and a second bottle *k* sufficiently to bring the rim of the bottle beyond 95 the leaf spring device which then engages the neck of the bottle and holds it in a suspended condition. In the morning when the door is opened the depository may be removed. The cover now is lifted and the 100 bottle *j* taken out whereupon the bottle *k* is shifted into the receptacle and taken out from the top.

In the described manner one milk bottle may be placed in the depository by the distributing milk man. However a family desiring two bottles or a bottle of milk and a bottle of cream may have placed one bottle into the depository and the other safely suspended therefrom as described.

It is impossible to remove the depository or a milk bottle therefrom as long as it is

hung on the door and the door closed. The cover or lid of the receptacle can not be opened for the removal of the milk bottle until the depository has been removed from the door. A single milk bottle is supported within the receptacle by the leaf spring device. If two bottles are deposited then one bottle is suspended from the leaf spring device which engages the bottle neck below its rim and the top bottle rests upon the top of the suspended bottle. Thus the leaf spring device performs two functions by virtue of its rising curved leaf springs leaving a central opening of proper size to allow of the suspension of a second bottle.

I claim as my invention:

1. A safety depository for milk bottles comprising a tubular receptacle, a leaf spring device in its bottom portion having upwardly curved, radial leaf springs extending inwardly and leaving a central opening, and a hinged cover at the top with a hook device rigidly secured thereto composed essentially of rectangular sections adapted to fit the top of a door.
2. A safety depository for milk bottles comprising a tubular receptacle, a hinged cover at the top with a hook device rigidly secured thereto composed essentially of rec-

tangular sections adapted to fit the top of a door, and means in the bottom portion of the receptacle allowing of the insertion and support of a milk bottle and of securely suspending a second one therefrom.

3. In a safety depository for milk bottles a leaf spring device in the bottom portion of the depository composed of a bottom ring with radial leaf springs formed integrally therewith extending inwardly and leaving a central opening, the said leaf springs yielding when the bottle is inserted and returning into the normal position to support the bottle and permit of suspending a second bottle by engaging with their inner ends the neck of the bottle below the rim.

4. In a safety depository for milk bottles a combined hinge cover and hook device composed of the hinged cover with two bars rigidly secured on its under surface, the said bars forming a rectangular hook beyond the hinge of the cover adapted to be hung on a door.

Signed at New York, N. Y., this 14th day of February, 1917.

MICHAEL CAGGIANO.
